Application March 13, 1929, Serial No. 346,704

7 Claims. (Cl. 103—161)

This invention relates to hydraulic pumps and motors of the high speed, multiple piston type.

For ease of explanation the machine herein-after described will be referred to as a pump although it functions satisfactorily as a motor, and, in fact, some of the novel features thereof have particular utility when functioning as such.

Pumps of this type are ordinarily operated continuously at constant speeds in excess of six hundred revolutions per minute, and are commonly called upon to deliver liquid at pressures in excess of one thousand pounds per square inch. Although in some instances they receive their entire supply of liquid at substantially atmospheric pressure from appropriate reservoirs, such pumps are more frequently so connected with the power transmission circuit as to receive their supply of liquid directly from the return side of the circuit. In some circuits, commonly known as "differential circuits", there is a difference between the rate of flow in the working side and the rate of flow in the return side of the circuit, so that the demand of the pump is sometimes greater and sometimes less than the supply actually furnished by the return side. Provision is ordinarily made, in installations involving differential circuits, for supplying liquid to the pump from an auxiliary source to make up for any deficiencies in the supply from the return side of the circuit, and also for permitting the escape of any excess liquid within the return side.

This is usually due to the use of a motor which has greater volumetric capacity when operating in one direction than in the other. The ordinary press cylinder and piston with a rod on one side only is such a motor. In many hydraulic presses this piston rod is made very large with the object of reducing the cylinder volume in the rod end to obtain a fast movement of the piston during the return stroke, using only the same flow of working fluid which imparts a slow movement on the working stroke.

With a piston rod which occupies one-half of the total cylinder volume, the return stroke will be twice as fast as the working stroke for the same rate of flow from the pump. During the working stroke the flow of the pump operates on the full area of the piston, while the piston movement is only expelling from the rod end of the cylinder an amount equal to one-half of this pump flow. The other half must be obtained from an auxiliary supply usually kept in reserve in a sump or oilpot.

During the return stroke the full flow of the pump is delivered to the rod end and acts on only

one-half of the full piston area. The piston, therefore, expels oil from the head end in quantity equivalent to twice the pump flow. The intake side of the pump can only receive one-half of this oil and the other half must be discharged into a reserve supply or sump. 5

When excess oil is to be discharged into the sump, it is not essential to have especially large passages thru which it may flow, as the full pressure of the pump is available on the rod end of the piston to force the return oil out of the head end of the cylinder. But when the returning oil is less than the amount discharged by the pump, there is no force available to raise the deficiency from the sump or reservoir and into the filling 10 pump cylinders, except the suction force due to atmospheric pressure. This makes it necessary to have large and direct passages to raise this make-up oil from the sump to the intake side of the pump without passing it thru the restricted 15 passages which are used to convey the oil to the external circuit connections as hereinafter described. 20

At the high speeds commonly employed the problem of filling each of the several pump cylinders within the exceedingly brief period allowed (ordinarily less than one twentieth of a second) is most serious even under the most favorable operating conditions. In pumps heretofore designed complete filling is impossible and in instances involving high differential (where the rate of liquid supply from the return side of the circuit is considerably less than the demands of the pump) such pumps have been known to run only 80% full. This failure to effect complete 25 filling not only reduces the volumetric efficiency 30 of the pump, but experiments show that it is also the primary cause of objectionable pump noise. 35

One object of the present invention is to increase the volumetric efficiency in pumps of the type mentioned. This is accomplished by a novel design and arrangement of ports and passages which afford, as near as practicable, a direct flow of liquid to the several pump cylinders, with a minimum resistance to such flow. The design 45 herein-after described is the result of extended experimentation and pumps embodying that design have demonstrated a volumetric efficiency of 96%.

Another object is to reduce pump noise. This 50 is accomplished in part as a consequence of the improved filling although we have discovered that part of the noise is due to the abrupt changes in pressure within each cylinder caused by the instantaneous exposure thereof to the high pres- 55

sures in the working side and to the low pressures in the return side of the circuit, alternately. This difficulty is overcome by a design of ports which render these pressure changes less abrupt.

- 5 Another object is the provision in a pump or motor of improved means effecting a hydraulic counter-thrust between pintle and cylinder barrel on the side of pintle opposite to the discharge port. The purpose of this thrust is to counteract 10 a combined mechanical and hydraulic thrust produced by the inward reaction of the pump pistons upon the cylinder barrel (tending to press it against the pintle) and the pressure of the oil in the discharge port which is forced out in a 15 film between the adjacent surfaces of cylinder barrel and pintle in the neighborhood of the port edges. This film pressure tends to lift the cylinder barrel away from contact with the pintle, and is in general greater than the piston pressures 20 which force the cylinder barrel toward the pintle. Attempts heretofore made to supply the necessary hydraulic balancing force to maintain close contact of cylinder barrel against pintle on the pressure side have been carried out by the 25 use of balancing ports extending only part way around the pintle and forming pockets which accumulate foreign matter and ultimately discharge it between the wiping surface with disastrous results.
- 30 Other objects and advantages will appear from the following description of an illustrative embodiment of the present invention.

In the drawings:—

35 Figure 1 is a sectional view of a pump embodying the several novel features of the present invention.

Fig. 2 is a sectional view taken in a plane at right angles to that of Figure 1.

40 Fig. 3 is an axial sectional view of the pump cylinder barrel applied to one end of the pintle.

Fig. 4 is a sectional view on the line 4—4 of Figure 3.

45 Fig. 5 is a sectional view of the other end of the pintle and taken substantially on the line 5—5 of Figure 2.

Fig. 6 is a sectional view of one of the two-in-take valves shown in Figures 1 and 2.

The pump shown is of the type described in the patent to Walter Ferris, No. 1,558,002, issued 50 October 20, 1925. It is supported and housed within an appropriate casing 10 having a hollow base 11 laterally extended to form a liquid reservoir 12 of ample capacity. It comprises an impelling means of a well known type including a 55 rotary cage 13, fixed to the end of a drive shaft 14 and journaled on fixed anti-friction bearings 15, the cage coacting with a rotary cylinder barrel 16, mounted on one end 17 of a pintle 18, to effect reciprocation of the several radial pistons 19 disposed therebetween. Each piston reciprocates 60 within a cylinder bore 20 in the barrel 16 so as to cause liquid to enter and leave the bore through an appropriate port 21. During rotation of the cylinder barrel upon the pintle end 17, each of the several cylinder ports 21 register alternately with upper and lower ports 22 and 23 formed in the pintle. In this instance the ports 22 and 23 constitute transverse gashes formed in the upper and lower faces of the pintle which communicate, 65 respectively, with upper and lower longitudinal passages 24 and 25 in the pintle. In this instance one end of the base 26 of each gash is acutely bevelled as at 27 so as to substantially merge with the cylindrical surface of the pintle.

(see Fig. 4) for a purpose which will hereinafter appear.

The other end 28 of the pintle 18 is anchored in an upright arm 29 rockably supported at its lower end upon a shaft 30. One end of shaft 30 is fixed in a lug 31, constituting an integral part of the rear wall of the casing 10, while the other end is fixed in a cylindrical block 32, removably fixed to the front wall of the casing. A large passage 33 (Fig. 2) in the rock arm 29 communicates with the lower pintle passage 25 through a tapered pintle passage 34, which, as indicated in Figure 5, is inclined with respect to the passage 25. A plug 35, inserted in and closing the end of the passage 25, is provided with a bevelled end 36 disposed substantially flush with the passage 34 and so inclined as to assist in bending the column of liquid in its flow between the passages 33 and 25. A second large passage 37 (Fig. 2) communicates with the upper pintle passage 24 through a similarly tapered and inclined passage 38 (Fig. 1) in the pintle, a similar plug 39 (Fig. 5) having a bevelled end 40 which serves in a similar manner to bend the column of liquid flowing between passages 37 and 24. A large pipe 41, whose lower end is submerged in the body of liquid in the reservoir 12, is fixed to the lower end of the arm 29 and communicates with the passage 33, and a second pipe 42, similarly mounted, communicates with the passage 37. The arrangement is such as to permit a direct and easy flow of liquid from the reservoir 12 to either of the pintle passages 24 or 25.

Each of the pipes 41 and 42 is provided with an inwardly opening check valve 43 of ample size 35 and preferably so designed as to offer a minimum resistance to admission of liquid thereto. One of these valves is shown in section in Figure 6. It comprises a casing 44 fixed to the end of the pipe and having a substantially bell shaped mouth 40 portion 45 containing an upwardly converging inlet opening 46. A hollow cup shaped valve element 47, seated over the opening 46, is provided with an annular bevelled face 48 for coacting with an appropriate valve seat 49 to normally close 45 the opening. Tail pieces 50 depending from the element 47 into the opening, and narrow guide webs 51 in the housing serve as centering means for the valve. Lugs 52 depending from the pipe limit the upward movement of the valve element 50 so as to insure a free flow of liquid around the valve element and into the pipe when the valve is elevated. It will be noted that the check valves 43 prevent the escape of liquid from either of the pipes to the reservoir 12.

A pair of longitudinal passages 53 in the shaft 30 communicate with one side of a hydraulic power transmission circuit (not shown) through a port 54 (Fig. 1) in the forward end of the shaft, and a second pair of passages 55 communicate with the other side of the circuit in a similar manner. Passages 53 also communicate with passage 37 in the rock arm 29 through a port 56 in the shaft and an upwardly inclined passage 57 in the arm (see Figs. 1 and 2); and passages 55 communicate with passage 33 in the arm through a similar port 58 and passage 59. Thus when the several pump cylinders discharge into the upper pintle passage 24 this entire discharge is directed through passages 37, 57 and 53 into one side of the circuit, the liquid returning from the other side of the circuit being directed through passages 55, 59, 33 to the lower pintle passage 25 and then back to the pump cylinders. When the pump is reversed the course of the flow is the same except in 70 75

the reverse direction, liquid from the return side of the circuit being directed to the pump cylinders through the passages 53, 57, 37 and 24.

In either case the entire pump discharge flows 5 downward through passage 37 or 33 and 57 or 59, respectively, in the rock arm, and thence through port 56 or 58 and the relatively constricted passages 53 or 55 in the shaft 30. The 10 return flow from the motor, which, as already explained, may be much larger or much less, must also be forced through the corresponding passages 55 or 53 in shaft 30 until it reaches port 68 or 70 which communicates through valve 63 and pipe 69 with spring loaded check valve 15 76 opening into sump, as later explained. If the return flow is in excess of pump discharge, the excess is forced back into the sump through the restricted ports and passages 55 or 53, 68 or 70, and 69 and 78, and the necessary head or pressure to compel this flow can readily be spared 20 from the available discharge pressure of 1000# per square inch. But if the return flow is less than the pump discharge, the deficiency must be raised from the sump by the intake suction of 25 the pump. In previous designs this was effected through an intake check valve formed in the valve casing 78, and the make-up oil had to pass up through the restricted passages 69, 68 or 70, and 55 or 53, the only force available for overcoming the resistance being the intake vacuum which also has to overcome all pintle and cylinder port losses.

As indicated in Figure 2 the passages 59 and 57 are preferably acutely disposed with respect to the passages 33 and 37, respectively, so that the liquid returning from the return side of the circuit through either of them and discharging at high velocity therefrom into one or the other of the passages 33 and 37 will produce an injector. 40 action therein tending to induce an upward flow of liquid through the associated pipe 41 or 42. This action assists the pump pistons in lifting liquid from the reservoir 12 in such quantities as to make up for any deficiency in the supply 45 from the return side of the circuit and thereby effect complete filling of the pump cylinders.

It will of course be understood that the pump is driven at constant speed in one direction only 50 through the shaft 14 and that the flow is reversed and regulated in a well known manner by rocking the arm 29 upon the shaft 30. In the pump shown this is accomplished by action of a plunger mechanism 60, similar to that disclosed in the patent above identified, operatively connected, as at 61, to the upper end of the arm.

Provision is made in the pump shown for permitting liquid to escape from the return side of the circuit in the event that that supply is in excess of that required to fill the pump cylinders. 60 The mechanism for this purpose comprises a shuttle valve 62, similar to the one described in the above entitled patent. This valve is housed in a casing 63 fixed to the lower end of the rock arm 29 between the pipes 41 and 42. This casing 65 contains a cylindrical bore having three spaced annular grooves 65, 66, and 67 formed in the wall thereof. Groove 65 communicates with passages 55 through a passage 68; groove 66 communicates with a discharge pipe 69; and groove 67 70 communicates with passage 53 through a passage 70. One end 71 of the bore communicates with the passage 68 through a passage 72 and the other end 73 of the bore communicates with the passage 70 through a passage 74. A piston valve 75 having three spaced heads 75, 76 and 77 is closely

fitted for lengthwise reciprocation in the bore. The lower end of the pipe 69 carries a spring loaded check valve 78 which permits liquid to escape from the pipe to the reservoir 12 whenever the pressure therein is sufficient to lift the valve element 79 thereof against the pressure of the spring 80.

The arrangement is such that when the piston valve is in the intermediate position shown in Figure 1 the central head 76 thereof covers the intermediate groove 66. When the pump is discharging liquid under pressure through the passages 33, 59 and 55 into the working side of the circuit this pressure is transmitted through the passages 68 and 72 to the right end 71 of the bore, causing the valve element to shift to the left and thereby open communication between grooves 66 and 67, so that the passages 53, communicating with the return side of the circuit, are then open to the pipe 69 and liquid from the return side, in excess of that required to fill the pump cylinders, may escape through the valve 78. Similarly, when the pump is discharging through passages 37, 57 and 53 into what is then the working side of the circuit the valve element is shifted toward the right under the pressure transmitted to the end 73 of the valve bore through passages 74 and 70, so that any excess liquid is free to escape from the then return side of the circuit through the passage 68, grooves 65 30 and 66, pipe 69 and valve 78. It will thus be noted that when the liquid supplied from the return side of the circuit is in excess of that required by the pump the pressure within the return side is determined by the tension in the spring 80 of the check valve 78. This may be varied by appropriate adjustment of the hollow plug 81 which is screwed into the valve casing and incidentally forms an outlet therefor.

Referring now to Figures 3 and 4 let it be assumed that the cylinder barrel 16 is rotating clockwise (Fig. 4) and that the pintle 17 has been shifted toward the left so that the pistons 19 in the lower half of their circular travel, are forcing liquid under pressure from the cylinders 45 into the lower pintle port 23 and passage 25 and, in the upper half of their circular travel, liquid returning from the return or low pressure side of the circuit is flowing into the cylinders. Under this condition of operation, the cylinder 50 barrel imposes a downward thrust upon the pintle, due to the aggregate or resultant thrust of the several pistons, which in this instance is upward, but which is more than overcome by the downward thrust imposed by the liquid under 55 pressure in the port 23 and by the liquid which has escaped outwardly from and around this port into the running fit between cylinder barrel and pintle and tending to separate them. This unbalanced thrust tends to increase the working 60 clearance between the cylinder barrel and the lower half of the pintle face and to decrease the clearance between the cylinder barrel and the upper half of the pintle face, tending to produce undue wear where the clearance is reduced and 65 undue leakage where the clearance is increased. In order to remedy this condition a hydraulic cushion is provided designed to counteract the effect of the unbalanced thrust thus imposed. In the pump shown this is accomplished in the 70 following manner.

Two pairs of grooves 82-83 and 84-85 are formed about the pintle, the grooves of each pair being equally spaced from the central plane of rotation of the cylinder barrel. Each of these 75

- grooves is uniformly tapered the upper half of each groove 82 and 83 of one pair being wider than the lower half and the lower half of each groove 84 and 85 of the other pair being wider than the upper half. (See Fig. 3.) Grooves 84 and 85 communicate with the upper pintle port 22 through a drilled passage 86 and grooves 82 and 83 communicate with the lower pintle port 23 through a drilled passage 87. Thus when the lower pintle port and the cylinders in the lower half of the circle are exposed to the high pressure side of the circuit this pressure is transmitted through passage 87 to the grooves 82 and 83, and by reason of the fact that these grooves are wider at the top than at the bottom, the hydraulic pressure therein produces a resultant upward thrust against the cylinder barrel to counteract the unbalanced thrust hereinabove described, and the cylinder barrel is thus maintained concentric with respect to the pintle with a uniform working clearance all around. When the pump is reversed so that the upper pintle port 22 and the cylinders in the upper half of the circle are exposed to high pressure, this pressure is transmitted to the grooves 84 and 85 and a similar hydraulic thrust is produced which tends to force the cylinder barrel down upon the pintle to thereby counteract the unbalanced upward thrust upon the cylinder barrel which normally exists under that condition of operation.
- By the use of endless grooves which completely encircle the pintle we avoid the formation of shoulders or faces which might tend to pick up or accumulate dirt or sediment contained in the hydraulic medium. In order to rid them of any such matter however we provide additional grooves 88 in the interior of the cylinder barrel into which such matter is thrown, by the centrifugal force resulting from the rapid rotation of the cylinder barrel. Discharge passages 89 leading from these grooves communicate with lengths of tubing 90 of sufficient length to resist the flow of liquid in any appreciable quantity therethrough but of sufficient diameter to carry off the very fine particles which may be contained in the grooves. This tubing is shown wrapped about the hubs of the cylinder barrel.
- In pumps of this type oil is ordinarily used as the hydraulic power transmitting medium because of its lubricating qualities, and the normal leakage between pintle and cylinder barrel is commonly relied upon to effect lubrication of those parts. Throughout limited areas bordering that pintle port 22 or 23 in which the oil is exposed to high pressure the lubrication is good but lubrication of other areas is more or less imperfect. In the pump shown provision is made for effecting a better and more uniform spread of the oil film between pintle and cylinder barrel. To this end two pairs of blind grooves 91-92 and 93-94 having no outlets are formed in the interior of the cylinder barrel completely encircling the pintle. Grooves 91 and 92 are equally spaced from and at opposite sides of the pintle ports 22 and 23, and grooves 93 and 94 are equally spaced from and beyond the grooves 91 and 92, respectively. Oil from that port 22 or 23 exposed to high pressure works its way lengthwise of the pintle and enters the grooves 91 and 92 establishing a pressure therein which is substantially uniform through the periphery thereof. These grooves then act as high pressure distributing mains from which the oil works in both directions along the pintle to form an oil film over the entire area of the pintle comprised

therebetween. Oil which works outwardly from these grooves is wiped around the pintle surface by the rapidly revolving cylinder barrel and its film thickness and pressure may become irregular, tending to produce deficient lubrication over part of the area. But when it enters the second pair of grooves 93 and 94 a uniform pressure throughout the periphery thereof is immediately established. These grooves then, acting as distributing mains, cooperate with the grooves 91 and 92 to provide a substantially uniform oil film over the pintle areas comprised therebetween. They also function in a similar manner to spread an oil film over those pintle areas comprised between them and the grooves 84 and 85. Grooves 84 and 85, beside their special balancing function already described, act as film re-distributing grooves in the same manner as grooves 91, 92, 93 and 94, already described.

As hereinabove pointed out one end of the base 26 of each of the gashes 22 and 23, constituting the upper and lower pintle ports, is bevelled off sharply, as indicated at 27 in Figure 4. This is for a purpose which will now be described. Let it again be assumed that the cylinder barrel is rotating clockwise and that the pintle has been shifted toward the left, as indicated in Figure 4, so that the several pistons in the lower half of their circular travel are executing a working stroke and in the upper half a suction stroke. Thus throughout the lower half of its circular travel, each piston and parts connected therewith are exposed to the high pressure (sometimes about fifteen hundred pounds per square inch) in the lower pintle port 23, and during the upper half of this travel each piston and connected parts are practically unloaded due to the low pressure (sometimes less than atmospheric pressure) in the upper pintle port 22. The bevelled portions 27 provide a tapered end for each pintle port by which the change from full load to no load, and vice versa, upon each piston, as it passes through each dead center position between the upper and lower halves of its circular travel, is rendered less abrupt, thus reducing the shock and the resulting noise as each cylinder full of low pressure oil is suddenly exposed to the oil in a high pressure port. For instance that piston and cylinder in horizontal position at the right of the pintle in Figure 4 is in dead center position, and having just completed a suction stroke there is practically no load thereon. Then as the cylinder barrel continues to rotate clockwise the port 21 thereof is gradually opened to the high pressure in the port 23 through the tapered end thereof, formed by the shallow gash 27, and the building up of pressure in the cylinder is obviously less abrupt than if the port were instantly opened by a square ended port. Similarly as each piston and cylinder passes through the other dead center position at the end of a working stroke, it remains under full pressure until the port 21 thereof is gradually opened to the low pressure port 22 through the tapered end thereof formed by the shallow gash 27. Again the transition from full load to no load is rendered less abrupt by reason of the tapered end of port 22, the compressed oil expanding gradually through the grooves and thus softening the noise, which results from a sudden expansion of a cylinder partly full of compressed oil and brought in communication with the low pressure port.

Various changes may be made in the embodiment of the invention hereinabove described without departing from or sacrificing any of the

advantages of the invention as defined in the appended claims.

We claim:—

1. In a reversible flow hydraulic pump the combination of a pintle, liquid impelling means rotatable thereon, intake and discharge passages in said pintle communicating with said impelling means, circulating passages fed from said pintle passages, a liquid supply source, conduits of a capacity not materially less than said pintle passages forming direct communications between said source and said pintle passages, respectively, and large capacity check valves permitting a free flow of liquid through said conduits from said source.

2. In a hydraulic pump the combination of a pintle, liquid impelling means rotatable thereon, intake and discharge passages in said pintle communicating with said impelling means, a liquid reservoir, a large conduit of a capacity not materially less than said pintle passages connecting said reservoir with said intake passage, a valve casing at the lower end of said conduit, said casing having an outwardly flaring inlet opening submerged within the body of liquid in said reservoir, and a hollow valve cooperating with said opening to freely admit liquid to said casing but preventing escape of liquid therefrom to said reservoir.

3. In a hydraulic pump the combination of a pintle, liquid impelling means rotatable thereon, intake and discharge passages in said pintle communicating with said impelling means, a support for said pintle, passages in said support communicating, respectively, with said pintle passages through the sides of said pintle, and plugs in the ends of said pintle passages, said plugs having bevelled ends forming deflectors for the fluid passing between said pintle passages and support passages.

4. In a reversible flow hydraulic pump the combination of a pintle, liquid impelling means rotatable thereon, interchangeable intake and discharge passages in said pintle communicating with said impelling means, liquid supply conduits leading to said pintle passages, respectively, check valves in said conduits, circulating passages com-

municating with said pintle passages, an outlet passage, a spring loaded valve for controlling the discharge from said outlet passage, and pressure responsive means for connecting said outlet passage with one or the other of said pintle passages selectively.

5. In a hydraulic pump or motor the combination of a pintle, liquid impelling means rotatable on said pintle and imposing a lateral thrust thereon, liquid conducting passages in said pintle, ports in said pintle for effecting communication between said passages and said impelling means, a pair of tapered grooves encircling said pintle at opposite sides of said ports and communicating with one of said passages, and a second pair of reversely tapered grooves encircling said pintle at opposite sides of said ports and communicating with the other of said passages.

6. In a hydraulic pump or motor the combination of a pintle, liquid impelling means rotatable thereon, passages in said pintle communicating with said impelling means, a groove encircling said pintle and communicating with one of said passages, and means permitting the escape of foreign matter from said groove, said means comprising a coil of small diameter tubing carried by said impelling means and communicating with said groove, the length of said tubing being such as to effectively resist the escape of liquid in any considerable quantities from said groove.

7. In a hydraulic pump or motor the combination of a pintle, liquid impelling means including an element rotatable on said pintle, passages in said pintle communicating with said impelling means, a groove in said element encircling said pintle and receiving working fluid from one of said passages and adapted by centrifugal action to effect precipitation of foreign matter contained in the fluid therein and a constricted vent for said groove through which foreign matter is removed by the restricted flow of working fluid therethrough.
